US00D769649S

(12) **United States Design Patent** (10) **Patent No.:** **US D769,649 S**
(45) **Date of Patent:** **** Oct. 25, 2016**

(54) **POSITIONAL PILLOW**

(71) Applicant: **Greendale Partners, Inc.**, West Covina, CA (US)

(72) Inventor: **Kevin Thomas Vargas**, West Covina, CA (US)

(73) Assignee: **Greendale Partners, Inc.**, West Covina, CA (US)

(**) Term: **15 Years**

(21) Appl. No.: **29/533,329**

(22) Filed: **Jul. 16, 2015**

(51) LOC (10) Cl. **06-09**

(52) U.S. Cl. **D6/601**
USPC ....

(57) **CLAIM**

The ornamental design for a positional pillow, as shown.

DESCRIPTION

FIG. 1 is a top, front and right-side perspective view of a positional pillow embodying my new design;

FIG. 2 is a bottom, front, and left-side perspective view thereof;

FIG. 3 is a top plan view thereof, the bottom plan view being a mirror image;

FIG. 4 is a left-side elevational view thereof;

FIG. 5 is a right-side elevational view thereof;

FIG. 6 is a front elevational view thereof; and,

FIG. 7 is a rear elevational view thereof.

1 Claim, 4 Drawing Sheets
